FIG. 3

Des. 187,307

PAGE 4

FIG. 4

Fig. 5

Figure 1 is a perspective view of a photographic printer machine showing our new design.

Figure 2 is a front view thereof.

Figure 3 is a rear view thereof.

Figure 4 is an end view thereof.

Figure 5 is an end view thereof opposite to that shown in Figure 4.

We claim:

The ornamental design for a photographic printer machine, as shown.
